CLAIM

The ornamental design for a wireless pressure testing unit, as shown and described.

DESCRIPTION

FIG. 1 is a perspective view of a wireless pressure testing unit;

FIG. 2 is a top view of the wireless pressure testing unit; FIG. 3 is a bottom view of the wireless pressure testing unit; FIG. 4 is a first side view of the wireless pressure testing unit;

FIG. 5 is a second side view of the wireless pressure testing unit;

FIG. 6 is a back view of the wireless pressure testing unit; and,

FIG. 7 is a front view of the wireless pressure testing unit. All broken lines illustrate portions of the wireless pressure testing unit that form no part of the claimed design.

UNITED STATES PATENT AND TRADEMARK OFFICE
CERTIFICATE OF CORRECTION

PATENT NO. : D821,236 S
APPLICATION NO. : 29/588536
DATED : June 26, 2018
INVENTOR(S) : Knoell et al.

Page 1 of 1

It is certified that error appears in the above-identified patent and that said Letters Patent is hereby corrected as shown below:

On the Title Page

Item (72) Inventor is corrected to read:
-- Maximillian Knoell, Racine, WI (US);
Timothy J. Alho, Pleasant Prairie, WI (US);
Bruce Engel, Milwaukee, WI (US);
Jason Horner, Burlington, WI (US);
Jin Kook Jeong, Gyeonggi-Do (KR);
Myeong Geun Cheon, Incheon (KR);
David F. Brekke, Frankville, WI (US);
Michael Gordon Holden, Milwaukee, WI (US) --

Signed and Sealed this
